Inventor:

R. D. Smith.

United States Patent Office.

ROBERT D. O. SMITH, OF WASHINGTON, DISTRICT OF COLUMBIA.

Letters Patent No. 79,019, dated June 16, 1868.

IMPROVED CONNECTING-ROD ADJUSTMENT.

The Schedule referred to in these Letters Patent and making part of the same.

TO ALL WHOM IT MAY CONCERN:

Be it known that I, ROBERT D. O. SMITH, of Washington, in the county of Washington, and District of Columbia, have invented a new and useful Improvement in Connecting-Rod Adjustments; and I do hereby declare the following to be a full, clear, and exact description of the same, reference being had to the accompanying drawings, in which—

Figure 1 is a side elevation, showing my device in position.

Figure 2 is a vertical longitudinal section of the same.

Figure 3 is an elevation of the check-washer.

Figure 4 is a cross-section of the connecting-rod showing the spline therein.

My invention consists in interposing somewhere between the ends of a connecting-rod, a screw-sleeve, or the equivalent of that device, and making said rod in two parts, to be united by said sleeve; so that by the turning of the sleeve, the distance between the ends of the rod may be increased or diminished without detaching either end of the rod from its wrist-connections.

That others may understand the construction and operation of my invention, I will particularly describe it.

In fig. 1 is represented a device for converting rotary into reciprocating motion. It is not, however, to be understood that my invention is confined to apparatus of that description, as I contemplate its application to any connecting-rod, for whatever purpose used in connection with moving machinery. It is contemplated as being particularly useful in the adjustment of valve-rods, harvester-pitmen, and in other like places, especially where frequent adjustment is sometimes required.

A is a balance-crank wheel, B B is the connecting-rod, and C a reciprocating lever. The connecting-rod B is made in two parts, and the adjacent ends are provided with screw-threads, the same being cut to the right hand on one part, and to the left hand on the other. The sleeve D is made with right and left-hand female screws, as shown in fig. 2, and the ends of the pitman or connecting-rod B are inserted, and screwed into said sleeve, as shown and described. Now it is very plain that if the two outer ends of the connecting-rod be attached to the wrist-pins, as at E and F, the distance between said points E and F may be increased or diminished, by rotating the sleeve D, because as the screw-threads run in different directions, the parts of the pitman or connecting-rod will be moved in opposite directions when the sleeve is rotated, and the effect sought is thus accomplished. For instance, in fig. 1, the stroke of the lever C will be from the points G to H. Suppose it is required for any purpose to change the position of said stroke, so that it will vibrate from I to J, it will be accomplished by turning the sleeve D until the wrist F has been brought to the point K, or the connecting-rod shortened that much, and this can be accomplished with the utmost ease, facility, and exactness, and, without detaching either wrist connection, as is now required where a screw-connection is made by screwing one end of the connecting-rod into a screw-head, as in harvester-pitmen.

In order to render the sleeve-connection rigid, check-nuts L L must be employed, which, when the adjustment has been completed, are screwed down hard against the ends of the sleeve. In some situations, however, check-nuts alone will not prove reliable, because any force applied to the main nut will operate directly, through frictional contact, to turn the check-nut also; I have therefore devised a check-washer, O, to be interposed between the main nut and check-nut, said washer being constructed and attached so that it cannot revolve on the screw, and therefore cannot transmit any rotary motion from one nut to the other. This washer is shown in fig. 3. It resembles any common washer, except that it is provided with a little tongue or projection, M, which fits in a spline, N, (fig. 4,) cut in the screw lengthwise with its axis. The operation of this washer is evident. The check-nut in being screwed down upon the main nut, does not exert any influence to turn it, if the washer with the tongue M is interposed, but the check-nut only operates to force the main nut against the threads of the screw in a direction parallel with the axis of the screw; whereas, when the washer is not interposed, or a common washer is employed, the frictional contact with the end of the main nut will be generally sufficient to cause that nut to turn slightly also, and in so doing, the adjustment will be changed, so that the use of said

washer, as described, will insure no alteration of adjustment in forcing the check-nut home, and it will also insure no change of adjustment, by reason of vibration or shocks administered to the nuts.

Having described my invention, what I claim as new, is—

A connecting-rod or pitman constructed in two parts, and united by the sleeve D with right and left screws, substantially as and for the purpose set forth.

A washer provided with an inward-projecting tongue, M, to be placed between a main and check-nut, in connection with a spline, N, cut in the screw, substantially as and for the purpose set forth.

R. D. O. SMITH.
